WEATHER STRIP CONSTRUCTION

William J. Dennis, Chicago, Ill., assignor to W. J. Dennis & Company, Chicago, Ill., a corporation of Illinois

Application January 31, 1938, Serial No. 187,794

10 Claims. (Cl. 20—69)

This invention relates to weather strip construction and particularly to a composite weather strip adapted for use in window casings having sash frames slidably mounted therein.

5 One object of the present invention is to provide a novel construction and arrangement in weather stripping whereby sticking or binding of the sash members or frames in their movement in the window casing is eliminated.

10 Another object of the invention is to provide a weather strip whereby rattling of the sash members in the window casing is prevented.

Another object of the invention is to provide a novel construction and arrangement wherein 15 efficient contact of the respective elements is maintained regardless of the expansion or contraction of the sash frames or the window casing.

Another object of the invention is to provide a weather strip of the character described which 20 eliminates the necessity of parting strips on the window casing, and which is adapted for use with standard sash frames without the necessity of extra or additional grooving of the sash.

A further object of the invention is to provide 25 a weather strip which is durable, economical, simple to install, and which will provide a maximum of protection against weather conditions to which the device may be subjected.

A still further object of the invention is to 30 improve devices of the character described in sundry details hereinafter referred to and particularly pointed out in the appended claims.

One embodiment of the present invention is shown for illustrative purposes in the accompanying drawing, in which:

Fig. 1 is a plan sectional view through a portion of a window casing and stops mounted thereon illustrating the application of my improved weather strip construction thereto before positioning the sash frames within the window casing;

Fig. 2 is a view similar to Fig. 1, illustrating the arrangement of the improved weather strip construction after the sash frames have been 45 positioned within the casing;

Fig. 3 is a fragmentary perspective view of a portion of my improved composite weather strip; and

Figs. 4 and 5 are fragmentary perspective views, 50 respectively, of oppositely disposed angle strips adapted to cooperate with the structure illustrated in Fig. 3, and forming a part of the present invention.

As illustrated in the accompanying drawing, 55 the present invention is shown in relation to a

portion of a casing member indicated, as a whole, by the numeral 6 having inner and outer stops 7 and 8, respectively, mounted thereon, and comprises an elongated intermediate member indicated, as a whole, by the numeral 9 and formed 5 of resilient sheet-like material capable of flexing in a manner to be positioned under tension between the casing 6 and inner and outer sash frames 11 and 12, respectively, as illustrated in Fig. 2.

The intermediate member is shown, in the present instance, as comprising an elongated substantially U-shaped projection 13 adjacent its central longitudinal portion to provide a hollow parting strip adapted to be positioned between 15 adjacent end and side portions of the inner and outer sash frames 11 and 12, respectively, as illustrated in Fig. 2, the member 9 being provided also with oppositely disposed wing portions 14 and 15 extending laterally from the respective 20 opposite sides of the projection 13 and terminating slightly short of the inner and outer stops 7 and 8, respectively, in a manner to permit a degree of lateral movement of the member 9 in either direction with respect to the stops 7 and 8. 25

Mounted in the casing 6 adjacent the respective inner and outer stops 7 and 8 are a pair of oppositely disposed angle strips formed of resilient sheet-like material, and indicated, as a whole, and respectively, by the numerals 16 and 17, the said 30 strips comprising leg portions 18 adapted to be positioned between the respective inner and outer stops and an adjacent sash frame to provide a metallic wearing surface along which the sash frames may slide, the said angle strips 16 and 17 35 being provided with a second leg portion 19 extending at an angle to the leg portion 18 and adapted to be positioned adjacent the casing 6 and between the inner face 21 thereof and the edge portion of the wings 14 and 15 formed on 40 the intermediate member 9, as clearly illustrated in Figs. 1 and 2.

It will be noted by reference to Figs. 1 and 2 that, owing to the resilient character of the material of which the angle strips 16 and 17 are 45 formed, the angle of the respective leg portions 18 and 19 thereof will be increased from that shown in Fig. 1 to that shown in Fig. 2, when the sash frames 11 and 12 are positioned in the casing 6, thereby placing the angle strips under a tension as illustrated in Fig. 2.

As illustrated in the drawing, the respective wings 15 of the intermediate member 9 are provided adjacent their outer edges with curved portions 22 forming concave surfaces on the side 55

thereof adjacent the casing 6, and the leg portions 19 of the respective angle strips 16 and 17 are provided with transversely curved portions having a convex surface on the side thereof adjacent the wings 14 and 15 and adapted to be engaged by the curved portions 22 thereof in a manner to lie substantially parallel thereto when the intermediate member 9 and angle strips 16 and 17 are in operative position with respect to the casing 6 and sash frames 11 and 12, as illustrated in Fig. 2, thereby providing a most efficient structure to reduce infiltration to a minimum and provide a maximum degree of protection against weather and atmospheric conditions to which the device may be subjected.

It will be noted by reference to Fig. 2 that the bearing or engaging portion of the respective sash frames 11 and 12 is adjacent the angle 23 formed by the respective sides of the projection 13 and the inner portion of the respective wings 14 and 15, and that by reason of the resilient character of the material from which the member 9 is formed and the relative position of the sash frames and weather strip with respect to the casing, the sash frames 11 and 12 are free to yield in a sidewise as well as an inwardly and outwardly direction and yet retain efficient weather-tight contact of the respective elements to provide an efficient weather strip construction. This feature is most desirable in view of the usual expansion and contraction of the sash frames due to weather conditions, in that the arrangement shown and described eliminates sticking or binding of the sash frames in the casing, and at the same time retains sufficient contact to reduce infiltration to a minimum and prevent rattling of the sash frames within the casing.

It will be observed from the foregoing description that in addition to the advantages above mentioned, the present invention eliminates the necessity of parting strips on the window casing, and that by reason of the hollow character of the projection 13 of the intermediate member 9, the weather strip of the present structure permits lateral movement of the sash frames with respect to the casing, and the projection 13 may be formed as to adapt the structure for use in connection with standard sash frames without the necessity of extra or additional grooving of the frames.

It will be observed also that the present invention provides a weather strip construction which is durable, economical, simple to install, and which will provide a maximum of protection against weather conditions to which the device may be subjected.

Obviously, the present invention is not limited to the precise construction and arrangement shown and described as the same may be variously modified. Moreover, all the features of the invention need not be used conjointly as the same may be used to advantage in variously different combinations and subcombinations.

What I claim as new and desire to secure by Letters Patent is:

1. In a window, the combination with a casing having laterally spaced substantially parallel inner and outer stops rigidly secured thereto, of an elongated member formed of resilient material positioned between said stops and laterally movable with respect to said casing member, and a plurality of elongated angle strips of resilient material positioned adjacent the respective stops and between the edge portions of said member and said casing and stops.

2. In a window, the combination with a casing having laterally spaced substantially parallel inner and outer stops rigidly secured thereto, of an elongated member formed of resilient material positioned between said stops and having a pair of elongated wing portions at opposite sides of the central portion of the member, said member being laterally movable with respect to said casing member and stops, and a plurality of elongated angle strips of resilient material positioned adjacent the respective stops and adapted to be engaged by the respective wing portions of said member.

3. In a window, the combination with a casing having laterally spaced substantially parallel inner and outer stops rigidly secured thereto and having upper and lower sash frames slidably mounted in said casing, of an elongated intermediate member formed of resilient material positioned between said stops and having an elongated substantially U-shaped projection adjacent its central longitudinal portion forming a parting strip between said upper and lower sash frames, said intermediate member being laterally movable with respect to said casing, and a plurality of elongated angle strips of resilient material positioned adjacent the respective stops and between the edge portions of said intermediate member and said casing and stops.

4. In a window, the combination with a casing having laterally spaced substantially parallel inner and outer stops rigidly secured thereto and having upper and lower sash frames slidably mounted in said casing, of an elongated intermediate member formed of resilient material positioned between said stops and having an elongated substantially U-shaped projection adjacent its central longitudinal portion forming a parting strip between said upper and lower sash frames, said intermediate member having elongated wing portions at the respective opposite sides of said projection and being laterally movable with respect to said casing member and stops, and a plurality of elongated angle strips of resilient material positioned adjacent the respective stops and adapted to be engaged by the respective wing portions of said intermediate member.

5. In a window, the combination with a casing having spaced inner and outer stops secured thereto and having upper and lower sash frames slidably mounted in said casing, of an elongated laterally movable intermediate member of resilient material positioned between the stops and between said sash frames and casing, said member having an elongated projection adjacent its central portion forming a movable parting strip between said sash frames and having elongated oppositely disposed wing portions at the respective sides of said projection, a plurality of elongated angle strips of resilient material positioned adjacent the respective stops and adapted to be engaged respectively by the wing portions of said intermediate member, the respective angle strips having leg portions positioned between the respective stops, and an adjacent sash frame, and having other leg portions positioned between the casing and respective wing portions of said intermediate member.

6. In a window, the combination with a casing having spaced inner and outer stops secured thereto and having upper and lower sash frames slidably mounted in said casing, of an elongated laterally movable intermediate member of resilient material positioned under tension between

- said stops and between said sash frames and casing, said member having an elongated U-shaped projection adjacent its central longitudinal portion forming a movable parting strip between
- 5 said sash frames and having elongated oppositely disposed wing portions at the respective sides of said projection, a plurality of elongated angle strips of resilient material positioned adjacent the respective stops and adapted to be engaged,
- 10 respectively, by the wing portions of said intermediate member, the respective angle strips having leg portions positioned between the respective stops and an adjacent sash frame, and having other leg portions positioned between the
- 15 casing and respective wing portions of said intermediate member.
7. In a window, the combination with a casing having spaced inner and outer stops secured thereto and having upper and lower sash frames
- 20 slidably mounted in said casing, of an elongated laterally movable intermediate member of resilient sheet-like material positioned under tension between said stops and between said sash frames and casing, said member having an elongated
- 25 U-shaped projection adjacent its central longitudinal portion forming a hollow movable parting strip between adjacent edge portions of said sash frames and having elongated oppositely disposed wing portions at the respective sides of
- 30 said projection, a plurality of elongated angle strips of resilient material positioned under tension adjacent the respective stops and adapted to be engaged, respectively, by the wing portions of said intermediate member, the respective angle
- 35 strips having leg portions positioned between the respective stops and an adjacent sash frame, and having other leg portions positioned between said casing and the respective wing portions of said intermediate member.
- 40 8. In a window, the combination with a casing having spaced inner and outer stops secured thereto and having upper and lower sash frames slidably mounted in said casing, of an elongated laterally movable intermediate member of resilient sheet-like material positioned under tension
- 45 between said stops and between said sash frames and casing, said member having an elongated U-shaped projection adjacent its central longitudinal portion forming a hollow movable parting strip between adjacent edge portions of said sash frames and having elongated oppositely disposed wing portions at the respective sides of said projection, said wing portions being curved trans-
- 50 versely adjacent their outer edges to provide a concave surface on the sides thereof adjacent said casing, a plurality of elongated angle strips of resilient material positioned under tension between and adjacent the respective stops, the respective angle strips having leg portions positioned between the respective stops and an adjacent sash frame and having transversely curved leg portions providing a convex surface on the side thereof adjacent said wings and positioned between said casing and respective wings in a manner to be engaged by the curved portions of said wings and to lie substantially parallel thereto when said intermediate member and angle strips are in operative position with respect to said casing and sash frames.
9. In a weather strip construction, the combination of an elongated intermediate member formed of resilient sheet-like material having an elongated U-shaped projection adjacent its central longitudinal portion forming a hollow parting strip and having elongated oppositely disposed wing portions at the respective sides of said projection, a plurality of elongated angle strips of resilient material positioned adjacent the said edge portions of the wings, the respective angle strips having leg portions positioned outside the respective edge portions of the wings and having leg portions positioned adjacent and engaged by portions of the respective wings adjacent the edges thereof when said intermediate member and angle strips are in operative position.
10. In a weather strip construction, the combination of an elongated intermediate member formed of resilient sheet-like material having an elongated U-shaped projection adjacent its central longitudinal portion forming a hollow parting strip and having elongated oppositely disposed wing portions at the respective sides of said projection, said wing portions being curved transversely to provide a concave surface on one side thereof adjacent the edge portions of said wings, a plurality of elongated angle strips of resilient material positioned adjacent the said edge portions of the wings, the respective angle strips having leg portions positioned outside the respective edge portions of the wings and having transversely curved leg portions providing a convex surface adjacent the respective concave curved portions of said wings and adapted to lie substantially parallel thereto when said intermediate member and angle strips are in operative position.

WILLIAM J. DENNIS.
